UNITED STATES PATENT OFFICE.

ELIAL M. STAPLES, OF ELIZABETH, NEW JERSEY.

GLARE-DIMMER.

1,252,193.

Specification of Letters Patent.

Patented Jan. 1, 1918.

Application filed December 5, 1916. Serial No. 135,228.

To all whom it may concern:

Be it known that I, ELIAL M. STAPLES, a citizen of the United States, residing at Elizabeth, in the county of Union and State 5 of New Jersey, have invented certain new and useful Improvements in Glare-Dimmers; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15 This invention relates to new and useful improvements in glare dimming devices for lights and consists of a simple and efficient device of this nature having various details of construction, combinations and arrangements of parts which will be hereinafter 20 fully described, shown in the accompanying drawings and then specifically defined in the appended claims.

My invention is illustrated in the accompanying drawings, in which:—

Figure 1 is a view in elevation of my improved dimming device.

Fig. 2 is a sectional view taken on line 2—2 of Fig. 1.

Fig. 3 is a sectional view on line 3—3 of Fig. 1.

Reference now being had to the details of the drawings by letter, A designates two sheets of wire netting of any mesh desired, 35 and B is a dimming member which may be of any suitable material, such as fabric of any kind, adapted to mellow the light and prevent the glare of the same. Said sheet of fabric is of circular outline and is adapted 40 to conform to the outline of lamps of different sizes and held therein in the same manner as the usual glass upon lights.

The sheet of dimming material covers, 45 preferably, a little more than half the area of the screen, the central portion, designated by letter C, extending below the transverse center for the purpose of covering the bulb which is to be centrally mounted in the reflector. Said sheet of dimming material 50 is placed between the two sheets of wire netting or screens and a binding D is stitched about and to the two sheets of screens and also through the marginal edge of the sheet 55 of dimming material and, in order to further hold the latter securely in place, the two screens and the sheet of dimming ma-

terial may be held frictionally together by corrugations E.

While I have shown the dimming material mounted between two sheets of screening 60 and stitched thereto, it will be understood that but a single sheet of screen may be employed, if desired, and the sheet of dimming material held thereto in any desired manner, the essential feature being the utilization 65 of a dimmer which will have a dimming material and which may replace the usual glass mounted in the lamp for vehicles or other purposes.

By the provision of a dimming device for 70 lamps especially designed for automobiles, etc., it will be noted that, in the event of anything striking the dimmer, it will yield without breaking and the light from the lamp will be diffused and the glare from 75 the usual lights avoided.

What I claim to be new is:—

1. A dimmer for lamps adapted to replace the glass of the front of the lamp, comprising screens, a sheet of dimming material intermediate the same, said screens being provided with corrugations for holding the parts together.

2. A dimmer for lamps adapted to replace the glass of the front of the lamp, 85 comprising screens, a sheet of dimming material intermediate the same, said screens being provided with corrugations for holding the parts together, and means for fastening the marginal edges of the screens and 90 sheet of dimming material together.

3. A dimmer for lamps adapted to replace the glass of the front of the lamp, comprising screens, a sheet of dimming material intermediate the same, said screens 95 being provided with corrugations for holding the parts together, the marginal edges of the screens and intermediate sheet of dimming material being stitched together.

4. A dimmer for lamps comprising two 100 semi-circular outlined sheets of wire mesh work screens with registering semi-circular outlined recesses formed therein, a sheet of dimming material intermediate the wire mesh work screens, said screens and intermediate sheet of dimming material being provided with a series of concentric corrugations.

5. A dimmer for lamps comprising two 110 semi-circular outlined sheets of wire mesh work screens with registering semi-circular outlined recesses formed therein, a sheet of

dimming material intermediate the wire mesh work screens, said screens and intermediate sheet of dimming material being provided with a series of concentric corrugations, and a binding fastened about the outer marginal edges of the screens.

6. A dimmer for lamps comprising two sheets of wire mesh work, adapted to replace the glass at the front of a lamp, a sheet of dimming material incorporated between said screens and fastened thereto, a

binding about the marginal edges of said screens and the sheet of screening material and stitched thereto, said screens and sheet of dimming material being further held together by corrugating the same. 15

In testimony whereof I hereunto affix my signature in presence of two witnesses.

ELIAL M. STAPLES.
